UNITED STATES PATENT OFFICE.

WILLIAM W. FORD, OF PITTSBURGH, PENNSYLVANIA.

NUT LOCK.

Application filed May 20, 1924. Serial No. 714,551.

To all whom it may concern:

Be it known that I, WILLIAM W. FORD, a citizen of the United States, residing at Pittsburgh, in the county of Allegheny and 5 State of Pennsylvania, have invented certain new and useful Improvements in Nut Locks, of which the following is a specification.

My invention relates to improvements in 10 nut locks, and is designed to provide a device of this type which may be economically manufactured from a rolled metal blank, having a main body portion punched out for passage of the bolt, and laterally arranged 15 wing extensions having integral resilient lug portions, bent outwardly from the body portion of the lock, at one or both sides of the central opening, and adapted to engage the side or sides of the nut.

20 The nut lock is made of a blank of a cross section adapted to provide for the bowing out of the main middle portion, between its terminal edges, so that it may be compressed in the action of screwing the nut 25 on a bolt, and will by its main body portion exert an outward spring tension against the nut, in addition to the individual spring tension and holding action of the individual lug or lugs.

30 The device is adapted to the positive holding of the nut, when screwed to position, and to permit of the turning of the corners of the nut over the resilient locking lugs, in screwing, and to permit of unscrewing of 35 the nut in the same manner, without impairment of the holding efficiency.

The present invention is generally similar 40 to the nut lock of Bartley Patent No. 1,198,515, of September 19, 1916, assigned to the present applicant, and has in view to overcome certain difficulties in manufacture 45 and to provide features of improvement in connection with the rolling of the blank and in the resulting article as manufactured.

45 In the prior nut lock of Bartley, the blank was sheared crosswise from a rolled metallic strip having a middle thickened portion, with the length of the nut lock approximating the width of the blank, and with the 50 partly severed resilient locking tongues extending inwardly at approximately right angles to or crosswise of the longitudinal fibre or grain of the rolled metal.

55 In my present improvement, I form the nut lock from a blank sheared crosswise from a rolled strip, preferably steel, but

with the width of the blank and finished nut lock corresponding to the width of the strip, and with the fibre or grain lengthwise of the article and its tongues. A further feature of advantage and novelty is in the disposition of the metal as to the thickened portion, by reinforcing the side or edge portions by continuously uniform main spring members, at each side of the middle bolt 60 hole, utilizing the middle thinner portion for the locking tongues.

One preferred embodiment of the invention is shown in the accompanying drawing, in which:

Fig. 1 is a view of the nut lock in front elevation, indicating the nut in position thereon in dotted lines;

Fig. 2 is a partial sectional view through a portion of a rail and fish plate, showing 75 the application of the nut lock to a bolt and nut;

Fig. 3 is a horizontal sectional view through the nut lock, on the line III—III of Fig. 1, and showing it in operative position and resiliently extended prior to tightening the nut to holding position;

Fig. 4 is a similar view showing the nut 80 screwed down to place and compressing the nut lock beneath it;

Fig. 5 is a perspective outer face view of the nut lock detached;

Fig. 6 is a face view from the rear;

Figs. 7 and 8 are cross sectional views on the lines VII—VII and VIII—VIII, respectively, of Fig. 5.

The nut lock or locking washer 2 of the present invention is formed from a rectangular blank sheared crosswise from a continuously rolled section of steel having a 90 smooth front and a middle rear channel 3 of minimum thickness approximating in width the diameter of the bolt hole 4 and between the outer reinforced or thicker edge portions 5, 5, as shown. The body portion 100 of the lock is slightly bowed outwardly lengthwise beyond the normal flat plane α , α , Fig. 5, so that under compression of the nut, the middle body portion may be pressed inwardly against the surface of the 105 fish plate, or of any other member secured by the bolt, corresponding to the said flat plane α , α . The nut lock, of tempered spring steel, when thus compressed by the nut when screwed tight, will exert a continuous tightening tension on the nut and bolt, compensating for any possible loosen-

ing due to wear of the threads or contacting parts, elongation, etc.

At one or both sides of the bolt hole 4, endwise, is a resilient tongue or locking ear 6, partly severed from the thinner middle channeled portion of the blank by a U-shaped punch opening 7. The tongue 6 as thus formed is integral with and forms a resilient depressible locking member for the nut. Its inner end is squared as at 8, for the full thickness at the middle and the outer corners are rounded as at 9, while the free end of the tongue extends outwardly beyond the face of the washer plate, for good bearing engagement against the flat side of the nut, as in Figs. 3 and 4.

The reinforced or thickened side portions 5 being longitudinal of the device at each side of the middle thin channeled portion 20 constitute the main elastic members of the plate, while being subject to the direct flattening pressure of the nut. The tongues 6, formed from the thinner middle portion, are freely resilient under the turning action 25 of the nut, and are easily depressed by the nut riding over their rounded corners, the tongues springing outwardly to holding engagement each time a flat side is presented.

A further advantage in the continuous 30 channel 3 is that ample clearance is provided, not only for the full under side of the tongues, but at each end, thereby facilitating removal of any accumulation of dust or other foreign matter or obstruction.

35 Due to the grain or fibre of the metal being lengthwise of the device, the side portions 5 and the tongues 6 will maintain their resiliency so that the lock may be used indefinitely, and may be subjected to successive applications and compressions without danger of breakage or deterioration.

The operation of the device is generally 40 similar to that of the Bartley lock, but is possessed of special advantages in construction, operation and economy, due to the arrangement of the metal and disposition of the parts in the manner shown.

What I claim is:

1. A nut lock consisting of a washer plate 50 having a middle longitudinal channel, providing a continuous thin middle portion, a bolt hole, and an integral resilient locking tongue extending inwardly towards the bolt hole and provided with rounded corners, the fibre or grain of the plate extending 55 lengthwise of the plate and said tongue.

2. A nut lock consisting of a washer plate having outer longitudinal thickened portions with an intervening longitudinal thin portion, a bolt hole extending through said 60 thin portion, and an integral resilient locking tongue partly severed from the thin portion extending inwardly towards the bolt hole and provided with rounded corners, the fibre or grain of the plate extending 65 lengthwise of the plate and said tongue.

3. A nut lock consisting of a washer plate having outer longitudinal thickened portions with an intervening thin portion, a bolt hole extending through said thin portion, and an integral resilient locking tongue partly severed from the thin portion extending inwardly towards the bolt hole and provided with rounded corners, 70 with a nut engaging terminal extending beyond the face of the plate, the fibre or grain of the plate extending lengthwise of the plate and said tongue. 75

4. A nut locking washer having a longitudinally concave inner face between a pair of longitudinal reinforcing ribs, one at each side of a middle thin portion providing said concave face, a bolt hole therethrough, and a partly severed resilient locking tongue formed from the thin portion extending 80 towards the bolt hole and provided with a nut engaging terminal having rounded corners, the fibre or grain of the plate extending lengthwise of the plate and said tongue. 85

5. A nut locking washer formed of a 90 blank sheared crosswise of a rolled strip whereby the fibre or grain of the strip is lengthwise, said strip having thickened reinforcing sides and a middle thin portion and arched to form a resilient compressible 95 plate, and provided with a middle bolt hole and a partly severed locking tongue formed in the middle thin portion.

6. A nut locking washer formed of a blank sheared crosswise of a rolled strip 100 whereby the fibre or grain of the strip is lengthwise, said strip having thickened reinforcing sides and a middle thin portion and arched to form a resilient compressible 105 plate, and provided with a middle bolt hole and oppositely disposed partly severed locking tongues formed in the middle thin portion, having their free resilient terminals confronting the bolt hole.

In testimony whereof I hereunto affix my 110 signature.

WILLIAM W. FORD.
